UNITED STATES PATENT OFFICE.

JASPER DERRY, OF MEDFORD, MASSACHUSETTS, ASSIGNOR TO ANDREW TERKELSEN,
OF BOSTON, MASSACHUSETTS.

STOP MECHANISM FOR PRESSES.

Application filed October 20, 1924. Serial No. 744,862.

This invention relates to mechanically operated power presses, and has for its object to provide simple and effective mechanism for automatically stopping the press when the ram or movable press element reaches the limit of its movement away from or toward the bed or stationary element, in the one case to permit the ready insertion and removal of the work, and in the other to hold the work under pressure, and for permitting the press to be manually started after having been automatically stopped in either position.

The more particular objects of the invention, together with means whereby the latter may be carried into effect, will best be understood from the following description of one form or embodiment thereof illustrated in the accompanying drawings. It will be understood, however, that the particular construction described and shown has been chosen for illustrative purposes merely, and that the invention, as defined by the claims hereunto appended, may be otherwise practised without departing from the spirit and scope thereof.

In said drawings:

Fig. 1 is a plan view of a press having stop mechanism embodying the invention.

Fig. 2 is a section taken substantially on the line 2—2, Fig. 1.

Fig. 3 is a section taken substantially on the line 3—3, Fig. 1, but showing the parts in a slightly different position to illustrate the operation of the stop mechanism.

Fig. 4 is a detail section taken substantially on the line 4—4, Fig. 3.

The frame of the press, as shown, comprises a pair of side uprights 10 having shoulders 11 upon which are supported the lower ends of four upright rods or posts 12, said posts above their lower ends being received and held in spaced upright position by hollow bosses 19 formed on the upper ends of the uprights. Adjacent their lower ends the posts 12 are threaded, as shown at 13, to receive nuts 14 by which is adjustably supported a bed plate 15, carrying the bed 16 or stationary element of the press. The ram 17, or cooperating movable element of the press, is formed with hollow bosses 18 which are guided upon the posts 12. The ram 17 is moved toward and from the bed 16 by means of a toggle 20 interposed between said ram and a cross-head 21 carried

by the posts 12. As herein shown, the cross-head 21 is slidably mounted on said posts and is normally held in engagement with nuts 22 on the latter by means of springs 23 interposed between said cross-head and nuts 24 on the upper ends of said posts, for the purpose more fully explained in a prior application filed February 18, 1924, Serial No. 693,478. The toggle 20 is straightened and broken to move the ram 17 toward and from the bed 16 by means of a link 26 pivotally connected at its forward end to the hinge pin 27 of the toggle and provided at its rear end with a slot 28 to receive a transverse cam shaft 29 journalled in the uprights 10, whereby said link is supported and guided. The link 26 is provided with a pair of spaced cam rollers 30 cooperating with the opposite sides of an edge-flange 31 formed on a cam 32 fast on the shaft 29, said cam operating to reciprocate the link 26 to alternately straighten and break the toggle.

Journalled in the uprights 10 is a transverse main shaft 33 disposed substantially parallel to the cam shaft 29 and adapted to be rotated from any suitable source of power, not shown. Fast on the shaft 33 is a pinion 34 (Fig. 3) which meshes with a gear 35 fast on a countershaft 36, also journalled in the uprights 10 and disposed parallel to the main shaft 33.

The countershaft 36 has splined thereto, for movement longitudinally thereof, a clutch hub 37 cooperating with a second clutch hub 38 formed as part of a pinion 39 rotatably mounted on the countershaft 36 and meshing with a gear 40 on the cam shaft 29. The hubs 37 and 38 constitute the elements of a clutch through which the cam shaft 29, and consequently the mechanism for operating the ram 17, may be operatively connected with or disconnected from the main or power shaft 33. The clutch hub 37 is movable longitudinally of the countershaft 36 to connect and disconnect the clutch by means of a clutch fork 41 formed at the end of one arm of a U-shaped lever 42 pivoted at 43 to a transverse frame member 44 connecting the uprights 10, the other arm of said lever 42 being connected by a link 45 with a hand lever 46 pivoted at 47 to a lug 48 on one of the uprights 10, said hand lever 46 constituting means for manually operating the clutch fork or shifter 41 to connect the clutch.

The clutch shifter lever 42 is formed with 110

an extension 49 provided with a cam roller 50 extended into the path of movement of a pair of dogs 51 pivoted at 52 to one face of the gear 40, said dogs having cam projections 53 for engaging the cam roller 50 and thereby operating the clutch shifter lever 42 to disconnect the clutch. The movement of the dogs 51 on their pivots 52 is limited by stop pins 54 and 55 projecting from the 10 face of the gear 40, the pins 54 being located in advance of the pins 55 with reference to the direction of rotation of said gear as indicated by the arrows on Figs. 2 and 3. The dogs 51 are normally held in engagement with the pins 54 by means of springs 56 connecting the same with pins 57 also projecting from the face of said gear, said dogs being however, adapted to yield against the tension of the springs 56 to the extent 15 permitted by the stop pins 55. The dogs 51 move in synchronism with the cam 32, and their positions on the gear 40, as determined by the stop pins 55, are such, with reference to said cam, that when the toggle 20 is fully 20 straightened or fully broken, thereby determining the limits of movement of the ram 17 toward and from the bed 16, the cam projection 53 of one of said dogs will engage the cam roller 50 and move the clutch shifter 25 lever 42 on its pivot 43 to disconnect the clutch.

In operation, the hand lever 46 is moved on its pivot to connect the clutch, as shown in Fig. 1, thereby starting the press and 30 causing a movement of the ram 17 toward or from the bed 16, as the case may be. As shown in Fig. 2, the ram is moving away from the bed, and as it approaches the limit of its movement in this direction the cam 35 projection 53 on one of the dogs 51 is brought into engagement with the roller 50. Said dog thereupon yields about its pivot 52 and against the tension of the spring 56 until brought into engagement with its stop pin 40 55, as shown in Fig. 3 and in full lines in Fig. 4. At this time the ram 17 has substantially reached the limit of its movement away from the bed 16, and, the yielding movement of the dog 51 having been arrested 50 by the stop pin 55, the cam projection 53 thereon operates to move the clutch shifter to disconnect the clutch and stop the machine. As soon as the cam roller 50 has been moved into the clutch disconnecting position, the cam projection 53 on the dog 51 55 will be snapped past said roller by the spring 56, as shown in dotted lines Fig. 4, thereby releasing said roller so as to permit the subsequent manual re-engagement of 60 the clutch when it is desired to start the machine. It will be understood that a similar stopping of the machine will be caused by the other dog 51 when the ram 17 reaches the limit of its movement toward the bed 65 16. In this manner the press is automatical-

ly stopped when the ram has been moved completely away from the bed in order to permit the ready insertion or removal of the work, and is also stopped when the ram reaches the limit of its movement toward the 70 bed to hold the work under pressure, the stopping means being, however, of such character as not to interfere with the manual starting of the machine whenever desired.

Having thus described my invention, I 75 claim:

1. In a power press, the combination with a bed and a ram, of mechanism including a rotary element and driving connections therefor for moving said ram toward and from said bed, means for disconnecting said driving connections, and dogs carried by said rotary element and having a limited yielding movement thereon for automatically operating said disconnecting means to arrest 85 the movement of said ram when the latter reaches the limit of its movement toward or from said bed.

2. In a power press, the combination with a bed and a ram, of mechanism including a rotary element and driving connections therefor for moving said ram toward and from said bed, a clutch for controlling said driving connections, a shifter for said clutch, a dog carried by said rotary element and having a cam surface for engaging and operating said clutch shifter to disengage said clutch, said dog being movably mounted on said rotary element, stops for limiting the movement of said dog, and a spring for normally holding said dog in engagement with one of said stops.

3. In a power press, the combination with a bed and a ram, of mechanism for moving said ram toward and from said bed, driving connections for said mechanism including a clutch, a shifter for said clutch, a pivoted dog moving in synchronism with said mechanism and adapted to operate said clutch shifter to disengage said clutch when said ram reaches the limit of its movement, and a spring for snapping said dog past said clutch shifter when said clutch has been disconnected to permit manual operation of said clutch shifter to re-engage said clutch. 110

4. In a power press, the combination with a bed, a ram, a shaft, and operative connections between said shaft and ram for moving the latter toward and from said bed, of a gear on said shaft, cooperating gearing including a clutch for driving the same, a shifter for said clutch, dogs carried by said gear and having cam surfaces adapted respectively to engage and operate said clutch shifter to disengage said clutch when said ram reaches the limit of its movement in either direction, said dogs being movably mounted on said gear, and springs for snapping said dogs past said clutch shifter when said clutch has been disconnected to permit 125 130

manual operation of said clutch shifter to re-
engage said clutch.

5. In a press, the combination of a move-
able press element, a driven shaft, mechanism
operated therefrom for moving said element,
a driving shaft for operating said driven
shaft, a clutch for disconnecting the same,
a rotary element on said driven shaft, a de-
vice mounted on said rotary element and ro-
10 tatable therewith into position to disconnect
said clutch to stop the rotation of the driven
shaft, and means for independently moving
said device out of clutch operating position
when said rotary element is in substantially
15 a position of rest.

6. In a press, the combination of a move-
able press element, mechanism connected to
said element for moving the same, a driven
shaft, a rotary cam carried thereby for shift-
ing said mechanism, driving means for said 20
driven shaft including a clutch, a lever for
operating said clutch, a device rotated from
said driven shaft, and means for supporting
said device to permit movement of the de-
vice in synchronism with said cam to shift 25
said lever and also to permit independent
movement of said device after shifting said
lever.

In testimony whereof I affix my signature.

JASPER DERRY.
